(57) **CLAIM**

The ornamental design for a spin coater, as shown and described.

DESCRIPTION

FIG. 1 is a front perspective view of a spin coater embodying our design;

FIG. 2 is a rear perspective view of the spin coater shown in FIG. 1;

FIG. 3 is a top view of the spin coater shown in FIGS. 1 and 2;

FIG. 4 is a front elevation view of the spin coater depicted in FIGS. 1-3;

FIG. 5 is a side elevation view of the spin coater depicted in FIGS. 1-4;

FIG. 6 is a rear elevation view of the spin coater depicted in FIGS. 1-5;

FIG. 7 is a side elevation view of the spin coater opposite that shown in FIG. 5;

FIG. 8 is a front perspective view of a spin coater embodying our design, with the display, rearmost portion of the cabinet, and a number of other features of the cabinet being shown in broken lines for illustrative purposes only and forming no part of the claimed design;

FIG. 9 is a rear perspective view of the spin coater shown in FIG. 8;

FIG. 10 is a top view of the spin coater shown in FIGS. 8 and 9;

FIG. 11 is a front elevation view of the spin coater depicted in FIGS. 8-10;

FIG. 12 is a side elevation view of the spin coater depicted in FIGS. 8-11;

FIG. 13 is a side elevation view of the spin coater opposite that shown in FIG. 12;

FIG. 14 is a front perspective view of a spin coater embodying our design, with all but the front portion of the cabinet being shown in broken lines, such that the remaining portion of the cabinet and a number of other features of the cabinet are shown for illustrative purposes only and form no part of the claimed design;

FIG. 15 is a rear perspective view of the spin coater shown in FIG. 14;

FIG. 16 is a top view of the spin coater shown in FIGS. 14 and 15;

FIG. 17 is a front elevation view of the spin coater depicted in FIGS. 14-16;

FIG. 18 is a side elevation view of the spin coater depicted in FIGS. 14-17; and,

FIG. 19 is a side elevation view of the spin coater opposite that shown in FIG. 18.

(Continued)

The broken lines are directed to environment and/or are for illustrative purposes only. None of the broken lines form part of the claimed design.

1 Claim, 19 Drawing Sheets
